SWIMMING POOL CHLORINATOR

Harry M. Clinton, Northridge, Calif., assignor to
Swimrite, Inc., Van Nuys, Calif.

Filed Dec. 15, 1970, Ser. No. 26,517

Term of patent 14 years

Int. Cl. D23—01

U.S. Cl. D23—3

FIG. 1 is a perspective view of a swimming pool chlorinator embodying my new design;

FIG. 2 is a side elevational view thereof;

FIG. 3 is a top plan view thereof;

FIG. 4 is a bottom plan view thereof;

FIG. 5 is an elevational view taken from the side opposite that shown in FIG. 2;

FIG. 6 is a fragmentary side elevational view of a modified form of the swimming pool chlorinator shown in FIG. 1;

FIG. 7 is a cross-sectional view taken along the line 7—7 of FIG. 6.

I claim:

The ornamental design for a swimming pool chlorinator, as shown and described.
